Primary Examiner — John Windmuller*Assistant Examiner* — Steven Czyz(57) **CLAIM**

The ornamental design for an oral care implement handle, as shown and described.

DESCRIPTION

FIG. 1 is a front right perspective view of a portion of an oral care implement handle according to the new design, the front left perspective view being a mirror image thereof; FIG. 2 is a rear left perspective view thereof, the rear right perspective view being a mirror image thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the article that form no part of the claimed design.
